UNITED STATES PATENT OFFICE.

WINFIELD S. RITCH AND SAMUEL W. PIDGE, OF FULTONVILLE, NEW YORK.

CLOTHESLINE SUPPORT.

Application filed March 3, 1923. Serial No. 622,611.

To all whom it may concern:

Be it known that we, WINFIELD S. RITCH and SAMUEL W. PIDGE, citizens of the United States, and residents of Fultonville,

5 in the county of Montgomery and State of New York, have invented a new and Improved Clothesline Support, of which the following is a full, clear, and exact description.

10 This invention relates to an attachment for clotheslines and has particular reference to a device for supporting the lower lead of an endless line from the upper lead thereof when the clothes are in place, whereby 15 to prevent undue sagging of the lower lead from the weight of the clothes.

One of the principal objects of the present invention is to provide a clothesline support of the character set forth which affords a 20 double bearing point on both leads of the line to overcome any tendency of the device to tilt and become disarranged.

As a further object the invention provides a clothesline supporting device which affords 25 a coupling with the lower lead of the line for movement therewith and this without pinching or squeezing the line to such an extent as to cause wear thereon.

As a still further object the invention contemplates a clothesline supporting device of 30 the character set forth which is extremely simple in its construction, readily applicable to the line, and which is inexpensive to manufacture and produce.

35 With the above recited and other objects in view, the invention resides in the novel construction set forth in the following specification, particularly pointed out in the appended claims and illustrated in the accompanying drawing, it being understood that the right is reserved to embodiments other than those actually illustrated herein to the full extent indicated by the general meaning of the terms in which the claims are expressed.

45 In the drawing—

Figure 1 is a side view of the supporting device in applied position.

Fig. 2 is an end view thereof.

50 Fig. 3 is a sectional plan view taken approximately on the line 3—3 of Fig. 1.

55 Referring to the drawing by characters of reference, A and B represent respectively the upper and lower leads of an endless clothesline and C generally designates a supporting device for supporting the lower

lead from the upper lead whereby the weight of the clothes on the lower lead equally distributes the strain on the upper lead A.

60 The device C is preferably constructed of a length of resilient material such as wire, which is bent upon itself to provide hooked portions 10 and 11 at its upper and lower ends for respectively engaging over the upper and under the lower leads of the endless clothesline. The upper hooked portion is of U-shaped formation as indicated at 13 and the side legs thereof are connected by spaced bights 12 to a pair of downwardly 65 converging legs 14, intertwined at 15. The remaining downwardly diverging legs 16 extending from the intertwined portion 15 are connected by spaced bights 17 to the lower hooked portion 11, which portion is 70 formed by the free ends of the material. The said free ends are then bent upwardly 75 and inwardly and downwardly at 18, the terminals 19 of which are arranged in contiguous parallel relation to provide a spring 80 tongue which is bent at 20 as illustrated in Fig. 2 to define together with the lower ends of the legs 16 a gripping portion for producing a lateral kink in the lower lead B of the line when the same is forced past 85 the bend 20 of the terminals and is gripped between the lower portion of the tongue and the lower ends of the legs 16. The bent portion 20 of the spring tongue defined by the terminals 19, together with the legs 16 90 provides in side view a flared entering mouth 21 for facilitating the entrance of the lower lead of the line. The bend 20 defines together with the legs 16 in side view a medially reduced or constricted portion 95 and the lower end of the tongue together with the lower end of the leg 16 a downwardly flared gripping space 23. The construction of this lower hooked portion produces in the line when hooked thereover, a 100 lateral kink D which couples the device or attachment C with the lower lead for movement therewith whereby the upper hooked portion 10 is caused to slide on the upper lead A. By producing longitudinally 105 spaced bights 12 and 17 in the hooked portions 10 and 11 a wide bearing for the device is afforded on each lead of the line to prevent tilting or displacement of the device when in supporting position or when moved with the line. One or more of these devices may be used in connection with a 110

line, depending upon the length of the same, whereby the weight of the clothes supported from the lower lead may be distributed on the upper lead, thus preventing undue sagging of the lower lead as is occasioned where no such a device is employed.

We claim:

1. A device for supporting the lower lead of an endless clothesline from the upper lead thereof, comprising a member having hooked upper and lower ends respectively engaged over the upper lead and under the lower lead, the said lower hooked end being bent to provide means for producing a lateral kink in the lower lead whereby the device is coupled with said lower lead for movement therewith.

2. A device for supporting the lower lead of an endless clothesline from the upper lead thereof, comprising a length of wire bent upon itself to provide hooked portions at its upper and lower ends, said hooked portions having each a pair of spaced bights for respectively engaging over the upper lead and under the lower lead of the line, the lower hooked portion having the free terminals of the bights bent inwardly to provide a resilient tongue for engagement medially with the portion of the line lying between the bights to produce a lateral kink therein whereby the device securely grips the lower lead for movement of the same therewith.

SAMUEL W. PIDGE.
